CANDLE PULL SOCKET

Charles E. Avery, Bridgeport, Conn., assignor to
Harvey Hubbell, Incorporated, Bridgeport,
Conn., a corporation of Connecticut

Application June 23, 1928, Serial No. 287,689

9 Claims. (Cl. 173—354)

This invention relates to a candle pull socket, and has for an object to provide a device of this type involving an improved construction and new arrangement of the insulating supporting member whereby it is easier to manufacture, and on which it is also easier to assemble the various elements of the switch mechanism and other elements of the device.

It is also an object of the invention to provide an improved means for mounting the switch mechanism.

It is a further object of the invention to provide a construction in which tubular enclosing shells of different lengths may be employed on the same socket construction.

It is a still further object of the invention to provide a socket construction in which improved mounting means therefor may be employed, and it is another object of the invention to provide an improved limit stop for the flexible switch operating means which will prevent pulling of the flexible means from the connection should undue strain be applied thereto after its movement has been arrested.

With the above and other objects in view, the invention consists in certain novel features of construction combinations and arrangements of parts as will be more fully described, constructions illustrating two different arrangements of the invention being shown in the accompanying drawings.

In these drawings,

Fig. 1 is a vertical section of the enclosing elements of a candle pull socket but showing a front elevation of the switch mechanism and the elements associated therewith.

Fig. 2 is a side elevation looking from the left of Fig. 1 with the enclosing elements removed.

Fig. 3 is a rear elevation looking from the left of Fig. 2.

Fig. 4 is a vertical central section.

Fig. 5 is a transverse section substantially on line 5—5 of Fig. 2.

Fig. 6 is a transverse section substantially on line 6—6 of Fig. 4.

Fig. 7 is a detail section showing the use of a single long fibre candle shell.

Fig. 8 is a detail section substantially on line 8—8 of Fig. 7.

Fig. 9 is a view similar to Fig. 1 but showing the preferred arrangement where the insulating body member is made of bakelite or similar material rather than porcelain.

Fig. 10 is a vertical section through this body member substantially on line 10—10 of Fig. 9.

Fig. 11 is a rear elevation of the device of Fig. 9 but with the enclosing tubes removed.

Fig. 12 is a top plan view of the device looking downwardly on Fig. 11.

Fig. 13 is a front elevation of the contacts of the switch mechanism showing how they are mounted on the insulating body.

Fig. 14 is a perspective view of the portion of the insulating body shown in Fig. 13 but with the movable switch element removed.

Fig. 15 shows a front and side elevation of the movable switch element.

The construction shown comprises an insulating body member 16 of suitable insulating material, such as porcelain, and as will be apparent from the drawings it is of substantially inverted L-shape with the transverse portion 17 at the top thereof. By this arrangement the insulating block portion of the socket may be made in one piece, and the space at the open inner side between the two portions gives plenty of room for the switch mechanism and the connections for the lead wires, leaving the outer or back portion of the body clear for an adjustable mounting means for the body. This arrangement also facilitates assembly, inspection and repair of the various elements and devices and these parts are all exposed and are easily accessible.

At the upper side of the transverse portion 17 are mounted the central lamp contact 18 and the screw shell contact 19 to receive any standard lamp 20 and engage the central lamp contact and the screw shell contact respectively. The screw shell 19 has an inwardly extending flange 21 by means of which it is secured to the end of the body by a screw 22 and an eyelet or rivet 23. The screw 22 is mounted in a longitudinally extending recess or channel 24 opening through the rear wall of the body 16 while the rivet 23 is in a recess or channel 25 in the front side of the portion 17. By providing these channels instead of openings the molding dies for the body and the operation of molding it is greatly simplified, and it is not necessary to have the longitudinally movable pins which would be required if openings were used.

On the front or flattened side of the upright portion of the body are formed inclined walls arranged as circular segments shown more clearly at 26 and 27, in Figs. 13 and 14, and they are separated by vertical walls 28. It will, therefore, be apparent that these walls are inclined so as to extend from the bottom of one wall 28 to the top of the next wall. The central lamp contact 18 is extended through an opening in the transverse

portion 17 in the body and has a segmental contact 29 mounted on the upper right hand wall 26. This element including these contacts, is preferably stamped from sheet metal and is mounted on the body by a rivet or eyelet 30 (Figs. 1 and 3) either extending through an opening in the body or molded therein. Mounted on the lower inclined wall 26 is a second stationary contact 31 secured to the body by a rivet or screw 32 and this contact has a binding post screw 33 for connection with a lead wire 34 from the house wiring system. The other lead wire 35 is connected to a binding post screw 36 mounted on a conducting member 37 secured to the body by a rivet 38. This member extends backwardly through an opening in the body and has a tapped opening for threaded engagement with the screw 22 for securing the screw shell 19 to the body. The screw 22, therefore, not only assists in mounting the screw shell on the body but it also forms an electrical connection between this screw shell and the conductor 37.

In the front wall of the upright portion of the body and surrounded by the segmental walls 26 and 27, is a recess or socket 39 to receive the inner end of a pivot pin or post 40, and in the bottom of this socket is a spring 41 tending to force this post outwardly. The outer or free end of this post is held by a support 42 which is secured to the body by suitable screws 43 extending transversely through the body. It is preferred that the head of the post be non-circular and that a similarly shaped recess be provided in the support 42 so that the post will be held against rotation. Mounted to turn on this post is a movable switch member 44 of sheet metal shown more clearly in Fig. 15 and it has wiping contacts 45 which are adapted to move about the post and alternately engage the inclined surfaces 27 and the stationary contacts 29 and 31 to bridge the same. The body portion of this movable contact has outwardly extending lugs 46 facing in opposite directions on opposite sides of the post and adapted to engage side walls of openings 47 in an oscillating operating member 48. This operating member is preferably a plate of pressed fibre so that it is of insulating material and it is pivoted on the post 40. The openings 47 are so arranged that the walls of diametrically opposite openings will alternately engage the lugs 46 on the movable switch member 44 as the member 48 is oscillated to rotate this switch member by a step by step movement, so that its wiping contacts 45 will alternately rest on the walls 27 to open the circuit or engage the contacts 29 and 31 to close the circuit. Embracing the post 40 outside of the operating member 48 is a coiled spring 49 one end of which extends into an opening 50 in the head of the post while the other end extends into an opening in the operating member 48. This spring, therefore, tends to rotate this operating member in one direction, which is clockwise as viewed in Fig. 1, and it also tends to slide the operating member 48 and movable switch member 44 inwardly or to the left along the post 40, as viewed in Fig. 4, to hold this movable contact against the stationary contacts 29 and 31 or the walls 27. It will be obvious that as the rear ends of the wiping feet 45 of the movable switch member pass off the rear ends of the stationary contacts 29 and 31 they will be forced inwardly to the bottoms of the vertical separating walls or shoulders 28 by the action of the spring 49 and will cause a swift break, obviating the liability of arcing when the circuit is

opened. It will be noted that as the post 40 is mounted directly at one end in the insulating body and at the other end on a support 42 which is independently secured to the body without connection to other elements, the post is fully insulated and the usual insulating means between the contacts and the pivot post is not required, thus greatly simplifying the construction. If it is desired to increase the tension of the spring 49 a screw driver may be inserted through the opening in the support 42 into a transverse slot 51 in the head of this post, and by forcing the post inwardly against the spring 41 to remove the non-circular head of the post from the similarly shaped recess in the support the post may be rotated to tighten the tension of the spring 49.

Secured to the opening member 48 is a hook or connector 52 and it is connected to this operating member above and to one side of its pivot post 40, and its connection to the member is a pivotal connection. At its free end this connector has a socket 53 to receive the end ball 54 of a flexible ball chain 55, and to facilitate connection of the chain this socket is slit at one side, as shown at 56, to permit passage of the connector 57 between the end ball of the chain and the next adjacent ball. The chain depends downwardly from this connector and passes through upper and lower guides 58 and 59 respectively carried on a support 60 which is secured to the body member 16 by any suitable means, such as an eyelet or rivet 61. The guides 58 and 59 are formed in laterally extending portions of this support 60, and besides guiding the chain they form limit stops to limit movements of the chain in opposite directions. For this purpose the upper guide 58 engages the socket 53 of the connector to limit downward movement of the chain while the lower guide 59 engages an enlarged ball of the chain or an enlarged connector 62 to limit upward movement of the chain, and therefore, prevent operation of the switch operating member 48 beyond certain limits. The upper guide 58 may have a tapered inlet 63 to receive the tapered lower end of the socket 53, as indicated in Fig. 7. When the chain has been pulled down to the limit of its movement to operate the switch, the coaction of these tapered walls will tend to press the sides of the socket 53 against the ball 54 and thus prevent these side walls spreading and permitting the ball to be drawn from the socket should the operator continue to pull on the chain with undue force.

These candle sockets are ordinarily mounted on fixtures which include a conduit enclosing the lead wires 34 and 35. The end of this conduit is shown at 64 and is threaded for threaded engagement with the tapped end portion 65 of the hickey or support 66. This end portion may have an extension 67 carrying a set screw 68 to engage the end of the conduit and prevent the hickey working loose on the conduit. These devices also ordinarily have a cupped member 69 which seats on a shoulder 70 on the conduit and to which it is held by the hickey. The particular hickey shown is an improvement over the old forms of hickeys. It includes an upright forked portion 71 thus providing a longitudinal slot 72 to receive the tapered head of a clamping screw 73. This upright forked portion extends longitudinally of the body 16 and is seated in a longitudinal recess 74 in the rear wall of this body. The screw 73 is threaded into a tubular metal member 75 mounted in the body and the screw projects, through a metal yoke 76. An insulating plate 73' may be

mounted between the inner end of the member 75 and the conducting member 37. This yoke is a metal plate curved to fit the curves of the body and is seated in a recess 77 therein, and its opposite ends are bent outwardly to form guide flanges 78 to engage the opposite sides of the upright portion 71 of the support, as shown in Figs. 2 and 3. It will be apparent that as the screw 73 is tightened its tapering head will clamp against the opposite sides of the support 71 and will tend to separate these side portions. This, however, will be prevented by the guide flanges 78 so that the screw will have a rigid clamping action with the support 71 and will rigidly hold the body of the socket in any adjusted position. It will be obvious that by loosening the screw 73 the socket structure may be moved up or down and clamped in adjusted position to give a long or short candle effect.

20 These candle sockets when in use are enclosed in tubular candle shells or casings. There are two general types of these shells commonly used, one made of glass and the other of fibre, and when in position they enclose the various electrical elements of the sockets and rest at their lower ends on the cupped member 69. In Fig. 1, I have shown a glass tubular casing 79, and where a glass casing is used a fibre or paper lining 80 is used between this casing and the electrical elements.

25 To hold this lining in proper position an outwardly extending lug 81 is provided on the body member, and in the present construction it may be conveniently formed as a part of the support 60. When the glass candle is used this lug projects outwardly to support the lining 80 which rests at its lower end on this lug, and then the whole thing is enclosed within the glass candle or casing 79. If, however, a fibre candle or casing is used this paper lining is unnecessary, but the casing should extend down to the cup 69. To accommodate this type of casing the lug 81 may be bent inwardly, as shown in Figs. 7 and 8, when the fibre casing 82, which is of practically the same diameter as the lining of the first form, 40 may be forced down over the device and rest at its lower end in the cup 69. In the old type of candle socket construction the lower insulating block was formed with a molded shoulder, and it will, therefore, be apparent that the socket was not adapted for use with both a glass candle casing and a fibre candle casing, so that an insulating block which was adapted for use with one type of casing was not adapted for use with the other type, necessitating the manufacture of two different types of 45 blocks or body members. In the present construction, however, the same body member may be used for both types of casings, and the socket structure when installed may be used with either type.

50 In the form of the device shown in Figs. 9 to 12 the elements have been arranged for use with a body member of a phenolic condensation product which is used for smaller sizes of candles. The switch mechanism and the arrangement of the screw and central lamp contact are the same in this form as in the first form. However, due to greater strength of the bakelite or similar material over that of porcelain the guide for the chain 55 may be molded into the body member. This is shown in Fig. 9 and comprises a channel 83 molded in the body member and having at its lower end a guide opening 84 in line with this chain for passage of the chain. The upper and lower ends of this channel guide form limit stops 75 for the chain the same as do the guides 58 and

59 of the first form, and the upper end 85 of the guide channel engages the tapered end of the socket 53 to prevent the side walls thereof separating under strain of the chain the same as in the first form.

Also due to the greater strength of this material for the body member the guide or yoke member 76 used in the first form for the upright support is not necessary. Therefore, as shown in Fig. 11, the rear wall of this body is provided with a longitudinally extending recess 86 for this support 71 and the side walls of this recess engage the side edges of this support, and these walls of the body have sufficient strength to prevent separation of the side portions of the support under action of the clamping screws 73.

It will be apparent from the foregoing description that the insulating support for the various elements of the socket and switch is made in one piece, and that the substantially inverted L-shape given to this member provides an ample space on the flattened or inner side of this member for mounting the various switch elements and associated members, leaving the back or rear wall of the body member entirely free for the adjustable support. Therefore, this adjustable support may be extended throughout substantially the entire length of the body permitting of a much greater range of adjustment than could be secured in the old constructions. Still further, in this construction and arrangement all of the elements of the switch mechanism are exposed and easily accessible, greatly facilitating the assembly of the various elements and the making of the connections to the lead wires.

Having thus set forth the nature of my invention, what I claim is:

1. In a candle pull socket, a substantially semi-cylindrical body member of insulating material, a support on the outer curved side for mounting the body and extending longitudinally thereof, means for securing the body to the support for longitudinal adjustment thereon, lamp socket contacts mounted on one end of said member, and switch mechanism mounted on the flat side of said body and having means for electrical connection with the lamp socket contacts.

2. In a candle pull socket, a substantially L-shaped insulating body member, switch mechanism mounted on the open inner side of said member and entirely supported thereby and movable as a unit therewith, a support for said member, lamp socket contacts mounted on the cross portion of said body member at the outer side thereof and electrically connected with the switch mechanism and means for securing the support to a fixture.

3. In a candle pull socket, a substantially L-shaped insulating body member, switch mechanism mounted on the open inner side thereof, a support for said member secured to the outer side thereof, screw shell and central lamp socket contacts mounted on the cross portion of the body member at the outer side of said member and electrically connected with the switch mechanism, and means for securing the support to a fixture conduit.

4. In a candle pull socket, a longitudinally extending substantially semi-cylindrical insulating body member, switch mechanism mounted on the flat side thereof including a rotary switch member, a central pivot post for said switch member mounted at one end in the body member, an outboard support for the post, a switch operating member mounted on said post, stationary switch

contacts mounted on the body member to cooperate with the movable switch member, central and screw shell lamp socket contacts mounted at one end of the body member, a connection from one 5 of said lamp contacts to one of the stationary switch contacts, means for connecting a lead wire to the other stationary switch contact, means for connecting a lead to the other lamp contact, and means for mounting the body member on a fixture.

5. In a candle pull socket, a substantially semi-cylindrical insulating body member, switch mechanism mounted on the flat side thereof and carried thereby and bodily movable as a unit therewith, said switch mechanism including a central pivot post mounted at one end in the body and extending therefrom, a movable switch member mounted to turn on said post, a switch operating member mounted on said post, stationary contacts mounted on the body in position to be bridged by said switch member, and means for operating the switch operating member.

6. In a candle pull socket, a substantially L-shaped insulating body member, switch mechanism mounted on the inner side of the upright portion of said member including a pair of stationary contacts and a movable switch member adapted to bridge said contacts, a pair of binding screws mounted below said switch mechanism, central and screw shell lamp socket contacts mounted on the cross portion of said body member, electrical connections from said lamp socket contacts to one of the stationary switch contacts and one of the binding screws respectively, and 35 an electrical connection from the other binding screw to the other stationary contact.

7. In a candle pull socket, an insulating body

member, switch mechanism mounted on said member including an oscillating member, a connecting member mounted on the oscillating member provided with an open ended socket having a slit side wall, a flexible chain having an end ball in said socket, and a guide for the chain arranged to engage the socket at opposite sides of its slit to limit movement of the chain and at the same time hold the side walls of the socket against spreading laterally under action of the ball.

8. In a candle pull socket, an insulating body member substantially inverted L-shape, switch mechanism mounted on the open inner side thereof, binding post screws mounted below the switch mechanism, central and screw shell contacts mounted on the outer end of the cross portion of the body member, said body having a longitudinal channel in its outer wall, means in said channel for securing the shell to the body and forming an electrical connection from said shell to one of the binding posts, said body having another channel opening through the opposite side of the cross portion, and a second securing means for said shell in said channel.

9. In a candle pull socket, an insulating body member of substantially inverted L-shape, central and screw shell lamp socket contacts mounted on the outer side of the cross portion of the body, switch mechanism and lead wire connecting means mounted on the inner side of the upright portion, suitable electrical connections between the socket contacts, the switch mechanism and said lead wire connecting means, and supporting means for the body member at the outer side 110 of said upright portion.
